HUM ELIMINATION

Charles J. Hirsch, New York, N. Y.

Application December 21, 1931, Serial No. 582,360

2 Claims. (Cl. 250—27)

This invention relates to an arrangement for utilizing rectified alternating current as a direct current source for energizing vacuum tubes. Particularly, it relates to radio receivers in which the ordinary home alternating current supply is rectified to furnish direct current voltages to the electrodes of the various vacuum tubes of the receiver. In this connection, the present invention effects a reduction in the expensive and heavy parts usually required, resulting in economy of design.

Heretofore it has been the practice to rectify alternating current usually by means of thermionic rectifiers and arrange a filter comprising inductance and capacity, for suppressing any alternating current components. Such practice has been effective in providing a hum-free source, but is expensive, and so those working in this art have continued to seek a more simple and inexpensive system, as well as one having greater economy in weight and size.

The primary object of the invention is to provide a hum-free path, which includes the various vacuum tubes of a radio receiver, by means of a bridge network and a thermionic vacuum tube, whereby it is possible to omit the usual inductance and capacity filter heretofore necessary to eliminate hum frequency currents present in the output of a rectifier of alternating current.

Another object of the invention is to provide a hum-free path which serves as a source of voltages for operating a vacuum tube receiver by the use of a bridged network and a vacuum tube, and to effect an additional economy by arranging this vacuum tube to act also as one of the operating tubes of the receiver.

Another object of the invention is to utilize a vacuum tube to provide a hum-free path which includes a radio receiver, in which the ordinary by-pass capacities of the radio receiver, together with the resistance of this vacuum tube, act as a filter to aid in freeing the path of hum.

The improvements of this invention include eliminating the usual inductance and capacity filter and substituting therefor a thermionic vacuum tube arranged in parallel with resistors proportioned in the ratio of μ to 1 (where μ is the amplification constant of the tube) to effect a bridge. By this arrangement all alternating currents are effectively balanced out in a path from the plate of the tube to the highest positive potential point of the power supply system, and thus provide what is termed a "hum-free path". In this path is located the load or work circuit

(generally a radio receiver), which requires hum-free voltages for operation.

In the preferred form of this invention, in which the hum-free path is utilized as a voltage supply for operation of a radio receiver, the exact balanced bridge arrangement previously referred to need not be strictly applied and may in fact be departed from to a considerable degree because of the fact that the radio receiver is primarily a system of cascaded vacuum tubes, including by-passing capacities across the points where voltages are applied to energize the tubes. The radio receiver, therefore, supplies the capacity element of a resistance-capacity filter, while the vacuum tube serves as the resistive element, to help smooth out any alternating-current or hum components and so lessens the requirement of exact bridge balance, which theory would otherwise require.

An additional economy is obtained by utilizing the vacuum tube, which acts to provide the hum-free path, for the additional purpose of acting as one of the amplifying vacuum tubes of the radio receiver.

The invention furthermore includes other features such as utilizing more than one tube to provide a hum-free path and includes the important feature of utilizing two tubes in a push-pull or balanced arrangement whereby the dual function of acting to eliminate hum and to amplify signals is better accomplished. In this arrangement the amplifying function is effected by the tubes operated in push-pull and hence differentially to the operation of the tubes, functioning to eliminate hum.

The push-pull arrangement permits the simultaneous functions of hum elimination and amplification of signals by two tubes while providing a balance against feed-back from the output to the input of the radio receiver. Furthermore, hum voltages present in the push-pull arrangement automatically balance out. The tubes thus function as amplifiers free from hum, and the resistance of the tubes is effectively present as the resistive element of a resistance capacity filter, as before mentioned, thus making unnecessary a perfect bridge balance against hum.

Having thus briefly described the invention, attention is invited to the drawings, in which:

Fig. 1 is a diagram of a circuit explanatory of the type of balanced or bridge vacuum tube circuit utilized;

Fig. 2 shows a circuit diagram of the preferred method of providing a hum-free path;

Fig. 3 is a circuit diagram of an alternative arrangement for providing a hum-free path;

Fig. 4 shows a circuit diagram which is a modification of Fig. 2, wherein a screen-grid type of vacuum tube is employed;

Fig. 5 is a circuit diagram showing, schematically, the method of utilizing a vacuum tube simultaneously to provide a hum-free path to operate a load requiring hum-free voltages, and to function as an amplifier;

Fig. 6 is a circuit diagram similar to Fig. 5, except that a push-pull arrangement of two tubes is shown;

Fig. 7 is a diagram illustrating a complete power supply system in which a single vacuum tube simultaneously provides a hum-free source of voltage for energizing a vacuum tube receiver and acts as an output amplifier of the receiver, and

Fig. 8 is a diagram illustrating a system similar to Fig. 7, in which a "pentode" type of vacuum tube functions to provide the hum-free operating voltages for a radio receiver, which is shown in detail, and functions simultaneously as the final audio amplifier of the receiver.

Thus, in Fig. 1, to which attention is now invited, E is a source of voltage, which may be either a direct current, or pulsating current source. "Pulsating current" is here used to indicate combined direct and alternating current such as occurs in the unfiltered output of a rectifier of alternating current. Terminals 11 and 12 include resistors 13 and 14 in series and paralleled by a load or work circuit 15 and vacuum tube 16. The connection of 16 is such that 14 is included in the grid circuit and 15 in the plate circuit. The resistors 13 and 14 are so chosen that the resistance of 13 is to the resistance of 14 as μ is to 1, where μ is the amplification constant of the vacuum tube 16. It is well known, and hence need not be mathematically demonstrated here, that when 13 and 14 are so proportioned, the current through the plate-cathode of 16, and hence through 15, is zero. That this is true will be evident from the definition of the amplification constant of a vacuum tube. As stated in Van Der Bijl "The Thermionic Vacuum Tube", page 160, "the value of the grid potential necessary to reduce the current to zero is

$$\left(\frac{E_p}{\mu}\right)^{\prime\prime}.$$

Here μ is the amplification constant and E_p is the plate-cathode potential. Therefore in Fig. 1, where the voltage E is applied to 13 and 14 in series, these resistors divide the voltage into a voltage drop across 13, which is the grid potential, and a voltage drop across 14, which is the plate potential (E_p), and since the ratio of 14 to 13 is μ , the condition for zero plate current is obtained as in Van Der Bijl's statement.

Fig. 2, again, has the voltage source E , which is here understood to be a pulsating current source, having a large direct-current component and an appreciable alternating-current or hum component, such as would appear in the output of a rectifier of alternating current. The elements having the same functions are numbered as in Fig. 1. Condenser 17, however, is inserted in the path or connection of 13 and 14 effectively to block or open the circuit for direct current. However, 17 is chosen to have a reactance which is low as compared with the resistance of 13 for alternating current frequencies which are present in the source E . The series

combination 13 and 17 is therefore essentially a resistance having a value μ times that of resistor 14, and hence no alternating current components present in source E will flow through the load 15 and plate-cathode path of tube 16. Direct current, however, will flow through this path and will be of a magnitude determined by the voltage E , the resistance of 15, the resistance of tube 16 (as determined by the voltage drop across 14, which thus serves as a grid bias), and the resistance of 14. 13 and 14 are therefore so chosen that, in addition to bearing a ratio equal to μ , their values determine the bias on the grid of 16 to permit direct current to flow through 15 sufficient to operate 15 as a humless source of direct current. As will be subsequently shown, it is contemplated that 15 shall be a complete, or the major part of, a radio receiver of the vacuum-tube type, requiring hum-free voltages for energizing the tubes.

The direct current voltage available from E is divided, of course, into a voltage drop across tube 16 and the constant hum-free voltage across 15. In a practical system, then, E is designed to be sufficiently high to provide for the drop across 15, 16 and 14, while allowing sufficient amplitude of voltage to act as an operative source for 15. Generally, it is feasible to choose values of 13 and 14 so that capacity 17 need not be a large and expensive unit. Where the rectified source E includes only a certain definite frequency component which must be eliminated, 17 may be chosen of smaller capacity, and an auxiliary condenser 18, shown in dotted line, may be arranged in shunt with 14 to give this portion of the circuit the same reactance as the branch 13 and 17.

Fig. 3 must be directly compared with Fig. 2 as it is an alternative arrangement and corresponding parts are similarly numbered. Here the condenser 17 of Fig. 2 is omitted and instead a condenser 19 prevents the direct current voltage drop across 14 from being applied between cathode and grid of 16. Condenser 19, however, is chosen to have a low reactance relative to resistance 14 for frequencies in source E which are to be suppressed so that the resistors 13 and 14, in the ratio of μ to 1, are effective in balancing out hum in the plate circuit path which includes the load 15. However, in order to predetermine the desired amount of direct current which flows in the plate circuit, a direct current bias of proper amplitude is provided and determined by tapping 14 at an appropriate distance from the cathode and leading this voltage to the grid via a high resistance 20. Resistance 20 should be high in value relative to the reactance of 19 so that it does not act as a short circuit. It will be clear, then, that here again is provided a hum-free path between 11 and the plate of 16 to serve as a source of hum-free direct current voltage to energize a load 15. As before, it is contemplated that E is the output of a rectifier of alternating current and that 15 is a vacuum-tube radio receiver or the major part of one.

Referring now to Fig. 4, the circuit is essentially the same as Fig. 2, except that a screen-grid type or four-element tube 16 is used. The screen 21 is connected to resistor 13 to provide it with proper positive potential relative to the cathode. This is possible without upsetting any of the balanced relations for eliminating hum, as previously described for Fig. 2.

Fig. 5 has all the essential elements of Fig. 2 to provide a hum-free path or source between the plate of 16 and terminal 11. Here, however, the

grid circuit includes the secondary of transformer 22, and the plate circuit includes the primary of transformer 23, the secondary of which energizes a loud speaker 24 indicated to be of the electro-dynamic type in that it includes a field winding 15', which is shown in parallel with the load 15. It has been found that a signaling voltage, shown as E₁ (which may, for example, be the audio output of a radio receiver requiring additional amplification), may be applied to the grid of 16 through 22, and thus be repeated in amplified form by 16 and 23 to operate speaker 24 without introducing any appreciable hum from source E in the speaker. Thus, the arrangement shown permits 16 to function simultaneously to provide a hum-free source of voltages and to provide a stage of amplification.

Fig. 6 shows another arrangement which is similar to that of Fig. 2 and Fig. 5 in that the arrangement of 13 and 14 is such as to provide the hum-free source between 11 and the plates of tubes 16 and in that the tubes 16 are used for the additional function of amplifying signals. Here, however, the tubes 16 are shown to be in a push-pull or balanced arrangement for the signals applied to input transformer 22' and output transformer 23'. In their operation for eliminating hum, the tubes 16 operate, however, in parallel since the voltage drop of E across 14 is applied in phase between cathodes and grids of tubes 16 and the drop across 13 and 17 is applied also in phase between the cathodes and plates of the tubes through load 15. Here load 15 is assumed to be a radio receiver the output of which is applied to transformer 22 so that tubes 16, in addition to providing the hum-free source for energizing 15, act as the final output amplifier of the radio receiver. One advantage of the push-pull arrangement here is that in addition to its well-known features of reducing distortion by the balancing out of even power harmonics, the audio voltage in output transformer 23' is conjugate to the path energizing 15; hence no audio voltage is passed back into the receiver 15 and audio feed-back is avoided.

In addition to the feature of hum elimination operating differentially to amplification and the feature of feed-back balance, a further advantage of the push-pull arrangement shown is that the requirement of the ratio μ to 1 for resistances 13 and 14 may here be departed from to a large degree; in fact, a hum-free receiver may result with 13 and 17 omitted. The reason for this is that hum voltages present in the source E, when applied to the push-pull tubes themselves, balance out in the output transformer 23 and hence the push-pull amplifier is itself unaffected by hum frequency components in its power supply. Furthermore, as has been indicated, the load 15 has been here definitely assumed to be the major part of a radio receiver, and its character as a load is therefore represented by capacity 26 and resistor 25.

This is a fair representation since the direct current input terminals of multi-tube receivers are always by-passed to close the radio frequency circuits and to prevent feed-back couplings through the power supply. Capacity 26 can therefore be considered as the shunt capacity element of a resistance-capacity filter. Similarly, the resistance of tubes 16 in parallel can be considered as the resistive element of this resistance-capacity filter. It will be clear then that the resistance-capacity filter is an effective unit in preventing

hum voltages from being applied to the receiver 15, and since the tubes 16, as stated, function as amplifiers independently of hum voltages in their power supply, it is not essential to preserve the bridge balance arrangement of resistances 13 and 14 in the ratio of μ to 1.

This last-mentioned advantage of the tubes 16 and capacity 26, forming a resistance-capacity filter, is also inherent in all of the other figures where 15 is the major part of a radio receiver 10 having by-pass capacities and hence is a general reason for not requiring an exact hum balancing arrangement of resistors 13 and 14.

Coming now to Fig. 7, a complete radio receiver is shown embodying all of the features of my invention as previously described, excepting the push-pull arrangement. Thus a transformer 21 has windings 28, 29, 30, 31 and 32. Winding 28 is the primary for attachment to the usual house-light circuit (not shown). Winding 29 serves to energize the cathodes of the vacuum tubes of radio receiver 15. Winding 30 energizes the cathode of rectifier 33 while high voltage is applied to the plates of 33 by winding 31. Winding 32 energizes the cathode of the amplifying and hum-eliminating tube 16. A center tap from 31 leads to condenser 34, which shunts the output terminals 11 and 12 to act as a partial filter so that the rectified voltage as developed across 11 and 12 is largely direct current with an alternating current or hum frequency component. The branch 13, 17, 14, as in the previous figures, proportions the voltage in the ratio of μ to 1. The hum-free path from 11 to the plate of 16 includes radio receiver 15 and output transformer 23, which supplies loud speaker 24. The output of 15 is supplied to the grid of 16 via input transformer 22. Electrostatic shield 38 is interposed between the windings of 22 and connected to 12.

Thus, in operation, transformer 27, tube 33, 40 and condenser 34 act as the usual power supply to provide a direct current source of power which contains hum at the terminals 11, 12. Due to the values of resistors 13 and 14, tube 16 functions to provide a hum-free source of voltage for operating radio receiver 15. The output of 15 is applied to the grid of 16, which acts also as an amplifier supplying the loud speaker 24 via transformer 23. The economy of this arrangement will be clear when it is remembered that the usual expensive hum-eliminating filter is omitted, and tube 16, which acts in place of the filter, also acts as the output tube of the radio receiver.

It was stated in connection with Fig. 6 that one advantage of the push-pull arrangement was that the signal was not fed back into receiver 15. While this advantage is not present in Fig. 7, described, nor in Fig. 8, which follows, yet it has been possible to use the single tube arrangement, and with careful choice of the circuit constants to achieve large amplification by 16 without the introduction of hum feed-back through receiver 15. Electrostatic shield 38 serves to prevent hum frequency voltages passing from terminal 11, via 15, electrostatically to the grid of 16 and thus aids in preserving the hum balance. It is clear that the push-pull arrangement of Fig. 6 could be used in Fig. 7 and Fig. 8.

The arrangement in Fig. 8 is similar to Fig. 7 excepting that a pentode type of tube is utilized for the hum elimination and final stage of amplification. Also, the circuit shown is com-

- plete as to the receiver and is in fact an actual circuit which has been in satisfactory use. The power-supply transformer 27, having windings 28, 29, 30, 31 and 32, and connected to rectifier 33 and condenser 34, acts exactly as the similarly numbered parts of the circuit of Fig. 7 in producing direct current voltage plus a hum frequency component at the terminals 11 and 12. Tube 16 has the screen 21 connected to 13, as in Fig. 4, to determine its voltage. The hum-free path from terminal 11 to the plate of 16 includes the load 15, which is the major part of a radio receiver, the speaker field 15' and by-pass condenser 15'' and also the output audio transformer 23, which feeds the loud speaker 24. The structure of the receiver 15 is not of itself a part of this invention and hence needs no detailed description other than to say that it employs three screen-grid tubes 35, 36, 37 arranged to constitute two radio frequency amplifying stages and a detector. The output of the detector 37 is arranged to include transformer 22, and in order to prevent any hum component which might flow from terminal 11 through the capacity between windings of transformer 22 to the control grid of 16 and hence regenerate and build up hum in the speaker 24, there is provided an electrostatic shield 38 grounded to terminal 12.
- The receiver 15 includes between the terminals marked - and + of the plate circuit of 16 the resistances 39, 40, 41, 42, whereby proper operating potentials having no hum are made available for feeding the screens and plates and furnishing proper grid bias to tubes 35, 36 and 37. The speaker field 15' is shown included in

parallel across this humless voltage source, and the by-pass condenser 15'' is also shunted across the + and - terminals to prevent the audio output of 16 being introduced back into receiver 15. Thus it will be seen that tube 16 provides a humless source of direct-current potentials for operating 15, and at the same time acts as an output amplifier for the receiver 15.

What is claimed is:

1. Means for supplying a load with a constant potential direct current from a variable voltage source comprising in combination a high resistance load requiring a high potential, a resistance, an amplifying vacuum tube connected in series with said load and said resistance, said resistance being included between cathode and grid of said tube, and a second resistance in series with a condenser in shunt with said load and the plate-cathode path of said tube, the ratio of said second resistance to said first mentioned resistance being approximately equal to the amplification constant of said vacuum tube.

2. In combination, a source of pulsating current, a path comprising a resistor, a capacity, and a second resistor in series shunting said source, a load circuit and the plate-cathode path of a thermionic vacuum tube connected in series shunting said resistor and capacity, the cathode-grid path of said tube shunting said second resistor, the resistance ratio of said first resistor to said second resistor being approximately equal to the amplification constant of said vacuum tube, and said load circuit comprising a high resistance across which a high constant direct-current voltage is developed.

CHARLES J. HIRSCH.
